UNITED STATES PATENT OFFICE

164,968

PHOTOGRAPHIC LENS MOUNT

Edward A. Springer, Irondequoit, and George K. Czarnikow, Greece, N. Y., assignors to Wollensak Optical Company, Rochester, N. Y., a corporation of New York

Application October 7, 1948, Serial No. 148,994

Term of patent 14 years

(Cl. D61—1)

To all whom it may concern:

Be it known that we, Edward A. Springer and George K. Czarnikow, both citizens of the United States of America and residents respectively of the town of Irondequoit and the town of Greece, in the county of Monroe and State of New York, have invented a new, original, and ornamental Design for a Photographic Lens Mount, of which the following is a specification, reference being had to the accompanying drawings forming part hereof.

Fig. 1 is a side elevational view of a photographic lens mount, showing the new design;

Fig. 2 is an end view thereof, viewed from the right-hand end of Fig. 1; and

Fig. 3 is an end view thereof, viewed from the left-hand end of Fig. 1.

The dominant features of the design comprise the relatively elongated tubular body with the three knurled rings as shown, the middle one of the knurled rings being arranged on a tubular body portion of slightly larger diameter than the body portions on which the other two rings are arranged, the body diameter being reduced through a generally conical transition just in front of the middle knurled ring and thence extending forwardly to the front end of the body through a length greater than the length from the conical transition to the rear end of the body. The three knurled rings are quite substan-

tially spaced from each other in an axial direction, through distances approximating the diameter of the mounting tube, thus enhancing the visual impression of ample smooth space between the knurled rings.

We claim:

The ornamental design for a photographic lens mount, substantially as shown and described.

EDWARD A. SPRINGER.
GEORGE K. CZARNIKOW.
